UNITED STATES PATENT OFFICE.

LOUIS WINKELMANN, OF HOBOKEN, NEW JERSEY.

VACUUM TUBE.

Application filed May 9, 1923. Serial No. 637,621.

This invention relates to vacuum tubes and particularly to devices of this class employed in connection with radio receiving and transmitting apparatus, and what are commonly known as amplifier or detector tubes, employing electrodes such as a filament, plate and grid; and the object of the invention is to provide a tube of the class specified with means for increasing or intensifying the active properties of the electrodes or elements of such tubes, said means comprising a radio-active substance or substances including phosphorous or a substance having the combustible properties of phosphorous which may be applied as a coating to the electrodes of the tube or which may be mounted upon the inner face of the tube to form a lining or facing therefore, and with these and other objects in view, the invention consists in a device of the class and for the purpose specified, which is simple in construction, efficient in use, and which is constructed as herein-after described and claimed.

The invention is fully disclosed in the following specification, of which the accompanying drawing forms a part, in which the separate parts of my improvement are designated by suitable reference characters in each of the views, and in which:—

Fig. 1 is a sectional side view of a vacuum tube made according to my invention.

Fig. 2 is a section on the line 2—2 of Fig. 1; and,

Fig. 3 is a view similar to Fig. 1 but showing a modification.

In Figs. 1 and 2 of the drawing, I have shown at 5 a vacuum tube commonly known as amplifier or detector tubes, as used in radio apparatus of various kinds and classes, said tube being provided with an end piece 6 having wire terminals 7 and within the tube or bulb proper 8 are the usual electrodes, namely a plate 9, filament 10 and grid 11, and in this form of construction the said electrodes are coated with a radio-active substance or substances as indicated at 9^a, 10^a and 11^a in Fig. 2 of the drawing, and this substance is also indicated in Fig. 1 by the stippling applied to said electrodes. It will be understood that any desirable radio-active substance or substances may be employed, such for example as radium, thorium, uranium, pitchblende or the like or a combination of two or more of such or other substances together with a combustible substance such for example as phosphorous or the like

or a combination of phosphorous or like substances with one or more of the radio active substances.

By applying the coating to the plate, filament and grid in the manner above set out, it has been found in practice that the utility of these electrodes is materially intensified to render vacuum tubes of the class specified more sensitive and efficient in accomplishing the results for which they are intended.

In Fig. 3 of the drawing I have shown another method of carrying my invention into effect, and in this figure, instead of applying or coating the electrodes 9, 10 and 11 with the radio-active substance or substances, I apply such substance or substances to the inner face of the bulb 8 of the tube as shown at 12 in said figure, and it will be understood that this coating is materially exaggerated in the drawing for the purpose of clearly illustrating the same, but on the other hand, the thickness of this coating may be regulated to suit vacuum tubes of different kinds and classes. It will be understood that the radio-active substance or substances and including phosphorous above named or any other equivalent substances may be used in the manner shown in Fig. 3 of the drawing to accomplish the desired result. It will also be apparent that the electrodes 9, 10 and 11 shown in Fig. 3 of the drawing may be coated as shown in Figs. 1 and 2 of the drawing if desired, but this matter will rest solely with the predetermined vacuum tube in connection with which the radio-active substance and phosphorous is employed.

In Fig. 2 of the drawing I have indicated in dotted lines this combination, or in other words, I have indicated the tube 8 coated as shown in Fig. 3 and it will be understood that either method of procedure may be employed or the combination as indicated in said figure. I find in practice that by surrounding the electrodes of a vacuum tube either by a coating of radio-active substance and phosphorous applied directly to the electrodes, or by a body of such substance encircling or surrounding the electrodes as shown in Fig. 3 or a combination of both of these methods, will operate to intensify or materially increase the active properties or functions of a specific vacuum tube, and the present invention is an improvement on similar methods of this class as shown and described in prior applications of Letters Patent of the United States, filed by me

September 6, 1921, Ser. No. 498,877, and April 10, 1922, Ser. No. 551,287, the former having issued in Letters Patent No. 1,466,777, dated April 4, 1923.

5 It will be understood that while I have shown and described a specific form of vacuum tube, that I am not necessarily limited to any type of tube of the class under consideration, my invention consisting particularly in the provision of a radio-active substance or substances which surround or encircle the electrodes of a tube of the class under consideration, and various changes in and modifications of the construction herein 10 shown and described may be made within the scope of the appended claims without departing from the spirit of my invention or sacrificing its advantages.

I have found that an inflammable or combustible emanative combination or mixture such as phosphorous and the like, combined with radio active substance or substances, will cause, when in contact with heat from a glowing filament thermionic emission current, the disintegration of all molecules or 25 elements into positive and negative particles within an evacuated tube, and by so doing attract and repel them through the thermionic emission stream as it flows to the positive and negative terminals, thereby 30 producing a smooth radiation. My construction also facilitates the making of tubes having like properties or values, thus producing an area within the tube suitable for 35 a perfect thermionic emission and rectification and amplification of radio waves and signals. It also strengthens and saves the filament from deterioration. Furthermore, less than one volt will operate the tube, and 40 the same will also stand considerable abuse, such as high voltage, vibration and continuous operation.

Having fully described my invention, what I claim as new and desire to secure by 45 Letters Patent, is:—

1. A vacuum tube containing electrodes and a substance comprising a radio active element and an element having combustible properties similar to phosphorous applied 50 directly to said electrodes.

2. A vacuum tube containing a filament, plate and grid coated with a combined radio active substance and a substance having combustible properties similar to phosphorous.

3. A vacuum tube containing electrodes and a radio active substance including a substance having combustible properties similar to phosphorous on one of said electrodes.

4. A vacuum tube containing electrodes and a radio active substance including a substance having combustible properties similar to phosphorous on one of said electrodes, and as a coating for the inner face of the tube.

5. A vacuum tube comprising a bulb within which is a vacuum chamber, electrodes in said chamber and the inner face of said bulb having thereon a substance containing a radio active element, and an element having combustible properties similar to phosphorous.

6. The combination with a vacuum tube containing electrodes positioned within the vacuum chamber of the tube, of a substance contained within said vacuum chamber and comprising a radio active element, and an element having combustible properties similar to phosphorous.

7. A vacuum tube containing electrodes and a substance comprising a radio-active element and phosphorous applied directly to all of said electrodes.

8. A vacuum tube containing a filament, plate and grid coated with a combination of a radio-active substance and phosphorous.

9. A vacuum tube containing electrodes and a radio-active substance including phosphorous on said electrodes and as a coating for the inner face of the tube.

10. The combination with a vacuum tube containing a filament, plate and grid of a substance containing a radio-active element and phosphorous within the tube and cooperating with the filament, plate and grid therein.

In testimony that I claim the foregoing as my invention I have signed my name this 3rd day of May 1923.

LOUIS WINCKELMANN.
